US00D986067S

(12) **United States Design Patent** (10) **Patent No.:** **US D986,067 S**
(45) **Date of Patent:** **** May 16, 2023**

(54) **SHAPED CONTAINER**

- (71) Applicant: **Silgan Containers LLC**, Woodland Hills, CA (US)
- (72) Inventors: **Andrew Palumbo**, Conshohocken, PA (US); **Thomas J. Snyder**, Westlake Village, CA (US); **Alvin Widitora**, Los Angeles, CA (US)
- (73) Assignee: **Silgan Containers LLC**, Woodland Hills, CA (US)
- (**) Term: **15 Years**
- (21) Appl. No.: **29/786,792**
- (22) Filed: **Jun. 2, 2021**

(57) **CLAIM**

We claim the ornamental design for a shaped container, as shown and described.

DESCRIPTION

FIG. 1 is a top perspective view of a shaped container, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The broken lines shown are included for the purpose of illustrating portions of the shaped container that form no part of the claim.

1 Claim, 7 Drawing Sheets
